COMBINED STOKER AND FIRE DOOR

Otto Moeller, Glendale, N. Y., and Paul A. Ketchpel, West Englewood, N. J., assignors to The Standard Stoker Company, Incorporated, a corporation of Delaware

Application July 23, 1932, Serial No. 624,236

15 Claims. (Cl. 110—101)

This invention relates to firedoors which are employed to close the firing opening of a furnace and more particularly to that type of firedoor which forms a roof or hood portion of a stoker discharge conduit adapted to deliver fuel into the furnace through the firing opening.

It is the principal object of our invention to provide a firedoor comprising a plurality of telescopically related segments which are movable to uncover the firing opening to permit access therethrough into the firebox.

It is also an object of this invention to provide a firedoor which is movable through an arc of approximately 90° and which comprises telescopically related segments forming a roof or hood portion for a stoker discharge conduit which communicates with the firing opening.

A further object of our invention is the provision of a firedoor comprising telescopically related segments which are movable upwardly through an arc of approximately 90° and which form a roof or hood portion for a stoker discharge conduit in communication with the firing opening, such upward movement of said telescopically related segments uncovering the firing opening to permit access therethrough into the firebox.

A still further object of this invention is the provision of a firedoor as above described but wherein a downward movement of the telescopically related segments uncover the firing opening to permit access therethrough into the firebox.

These and other objects such as the novel construction and relation of parts one with another will be hereinafter described in the following specification and illustrated in the accompanying drawings forming a part thereof.

On these drawings:

Fig. 1 is a central vertical longitudinal view of the rearward portion of a locomotive showing the invention in position with portions broken away;

Fig. 2 is a central vertical longitudinal view of the rearward portion of a locomotive showing the invention in elevation with portions of the operating motor therefor in section;

Fig. 3 is a view similar to Figures 1 and 2 showing a modified form of the invention; and

Fig. 4 is a transverse section taken on the line 4—4 of Fig. 3 with parts broken away and removed.

The invention is shown as being applied to a locomotive A having the firebox 10, the firing opening 11 in the firebox backwall 12 and a deck

13 which extends rearward of said backwall and supports a cab 14.

Extending forwardly from the tender (not shown) is a stoker generally indicated by B which includes a conduit 15 and a curved nozzle or discharge conduit 16 secured to the backwall 12 and arranged to discharge fuel into the firebox through the firing opening 11. The conduit 15 and the nozzle 16 are flexibly connected at their adjacent ends as at 17 to permit articulation therebetween. A distributing plate 18 extends forwardly from the discharge conduit 16 through the firing opening 11 and, in conjunction with a pressure fluid head 19, distributes fuel to all parts of the fire.

The discharge conduit 16 at its upper portion and directly opposite the firing opening 11 is opened or apertured as at 20, through which aperture access to the interior of the firebox may be had. Covering this aperture 20 is a door 20 comprising a plurality of segments 1, 2, 3, and 4 arranged to slide one within the other which in the preferred form of our invention are arranged to uncover the firing opening by a downward swinging movement. These segments are all hinged at their lower ends about the stub shafts 21 and their respective contacting surfaces are formed on radii which are coaxial with the axes of the stub shafts 21. At their forward edges, each of the segments 1, 2, and 3 is provided with a downwardly projecting lip such as 22 so that when the segment 1 is swung downwardly and rearwardly it will slide over the segment 2 until the lip 22 engages the forward edge of the segment 2 causing downward swinging movement thereof together with the segment 1 over the segment 3.

It will be observed that the continued downward movement of the segment 1 will cause the segments 1, 2, and 3 to slide over the segment 4 and then these segments will continue their downward movement until they are brought to rest in the position indicated by the conventional lines in Figure 1, at which position an opening of sufficient size has been uncovered which will permit manual firing or the inspection of the firebox. In order to return the segments to their normal position, each of the segments 1, 2, and 3 is provided at one of its lower ends with an outwardly extending lug such as 23, the lug of the segment 1 contacting the rear edge of the segment 2 and, also, the lugs of the segments 2 and 3 each in turn contacting the rear edge of the segments 3 and 4, respectively. Thus, when the segment 1 is swung upwardly the lug of each

respective segment will draw along the segment which it contacts, thereby closing the aperture 19.

Preferably, power means is employed for actuating our novel firedoor and in the present instance it comprises a pressure fluid motor M which includes a cylinder 24 housing a piston 25, the movements of which are controlled by a valve 26 operable through the foot pedal 27 disposed above the cab deck 13. The piston 25 is connected to one end of a rod 28 while to the opposite end of this rod there is connected a cross-head 29 which is reciprocably mounted in the guideway 30. A link 31 connects the cross-head and segment 1 of the firedoor.

In the normal operation of the stoker, the firedoor is in a closed position and the piston 25 is in the position as shown in Figure 2. Pressure fluid is supplied to the valve chamber 32 by a lead 33 and from there passes into the cylinder 24 through the port 34, thus holding the piston in its upward position and thereby preventing the opening of the firedoor should an explosion occur in the firebox. Whenever it is desired to open the firedoor, the fireman depresses the pedal 27 with his foot causing the valve 26 to move upwardly. Pressure fluid from the valve chamber 32 will then enter the port 35 at the upper end of the cylinder 24 and move the piston 25 downwardly, and the pressure fluid in the cylinder 24 below the piston 25 will pass into the atmosphere through the exhaust ports 36. This downward movement of the piston 25 will pull the segment 1 through the connecting link 31 and thus cause the telescopically related segments to be swung downwardly as previously described to the position indicated by the broken lines in Figure 1.

When it is desired to close the firedoor, the fireman removes his foot from the pedal 27, and since the valve 26 is unbalanced by having a piston 37 at its lower end of larger diameter than the piston 38 at its upper end, the valve and its associated foot pedal 27 will return automatically to the position shown in Figure 2. The pressure fluid in the chamber 32 then enters the cylinder 24 through the port 34 at the lower end thereof and returns the piston 25 to its original position. During this operation, the pressure fluid in the cylinder above the piston evacuates through the port 35 to atmosphere. The upward movement of the piston 25 causes the segment 1 to swing upwardly and thus draw the other segments 2, 3, and 4 by means of the lugs 23 which extend inward from the segments 1, 2, and 3 and contact the rear edges of the segments 2, 3, and 4 respectively.

In the modified form of the invention which is best illustrated in Figure 3, the aperture 50 in the discharge conduit 16 is opened by an upward swinging movement of the firedoor, which firedoor comprises the segments 51, 52, and 53 arranged to slide one within the other, each of which is provided with a pin such as 54 which extends upwardly from the outer surface of the segment. The segments 52 and 53 are provided with arcuate grooves 55 and 56 respectively, which receive the upwardly extending pin in each of said segments 51 and 52. Embracing the firing opening 11 is a frame 57 which is formed with the discharge conduit 16 and which is provided with a rearward extension 58. The underside of the roof portion 59 of the extension 58 is grooved as at 60 to receive the pin 54 of the segment 53. The segments 51, 52, and 53 are mounted on stub shafts such as 61 and are operable by a pressure fluid motor M' which is similar to the motor M

of the preferred form of our invention with the exception that the piston thereof moves upwardly when the foot pedal 62 is depressed and moves downwardly when the fireman removes his foot from the pedal 62. The cross-head 63 of the motor M' is mounted to reciprocate in the guideway 64 and a link 65 connects the cross-head 63 with an ear 66 which extends outwardly from the segment 51.

In the operation of the modified form of our invention, the upward movement of the cross-head 63 swings the segment 51 in an upward direction. In its upward travel the forward edge 67 of the segment 51 engages the lip 68 of the segment 52 causing this segment to swing upwardly and forwardly until the segment 53 is similarly moved beneath the extension 58. The segments 51, 52, and 53 are then in the position shown by the broken lines in Figure 3, thereby permitting access into the firebox through the aperture 50 and the firing opening 11. When the fireman releases the pedal 62, the cross-head 63 returns to the position shown in Figure 3. During the downward movement of the cross-head, the segment 51 is swung downwardly and the pin 54 thereof engages the rear edge 69 of the segment 52 and pulls it downwardly. It is of course, apparent that the continued downward movement of the segment 51 will close the firedoor by returning the segments 51, 52, and 53 to their original position, the pin 54 of the segment 53 engaging the rear edge 70 of the extension 58 thereby arresting further downward movement of the segments.

While our invention has been illustrated and described in connection with a stoker it will be readily seen that the essence of this invention is the provision of a firedoor which comprises a plurality of segments arranged to slide one within the other, and the firedoor does not necessarily need to be constructed of arcuately shaped segments nor is it limited for use with stoker fired boilers alone. The present invention contemplates the use of our invention in connection with the various forms of doors now in use, such as the well known vertical door which is in use on many locomotives. The various uses of our invention are defined by the appended claims.

We claim:

1. In combination with a firebox having a back-wall provided with a firing opening therethrough, a stoker discharge conduit attached to said back-wall and delivering fuel to said opening, the upper portion of said discharge conduit being open opposite said firing opening and a door for said firing opening forming a hood for the open portion of said discharge conduit, said door comprising a plurality of segments arranged to slide one within the other, and means for moving one of said segments for partially uncovering said firing opening, the continued movement of said segment causing movement of the next succeeding segment for further uncovering said firing opening.

2. In combination with a firebox having a backwall provided with a firing opening therethrough, a stoker discharge conduit attached to said backwall and delivering fuel to said opening, the upper portion of said discharge conduit being open opposite said firing opening and a door for said firing opening forming a hood for the open portion of said discharge conduit, said door comprising a plurality of segments arranged to slide one within the other and means for moving one of said segments downwardly for partially un-

covering said firing opening, the continued downward movement of said segment causing downward movement of the next succeeding segment for further uncovering said firing opening.

5 3. In combination with a firebox having a backwall provided with a firing opening therethrough, a stoker discharge conduit attached to said backwall and delivering fuel to said opening, the upper portion of said discharge conduit 10 being open opposite said firing opening and a door for said firing opening forming a hood for the open portion of said discharge conduit, said door comprising a plurality of segments arranged to slide one within the other, and means for moving one of said segments upwardly for partially uncovering said firing opening, the continued upward movement of said segment causing upward movement of the next succeeding segment for further uncovering said firing opening.

20 4. In combination with a firebox having a backwall provided with a firing opening therethrough, a stoker discharge conduit attached to said backwall and delivering fuel to said opening, the upper portion of said discharge conduit being open 25 opposite said firing opening and a door for said firing opening forming a hood for the open portion of said discharge conduit, said door comprising a plurality of segments arranged to slide one within the other, each of said segments having means adapted to engage its next succeeding 30 segment for limiting the movement of said segments relatively to each other, and means exterior of the conduit for moving one of said segments along the next succeeding segment for 35 partially uncovering the firing opening, continued movement of said first named segment causing the remaining segments by reason of their engaging relation to be successively moved to further uncover said firing opening.

40 5. In combination with a firebox having a backwall provided with a firing opening therethrough, a stoker discharge conduit attached to said backwall and delivering fuel to said opening, the upper portion of said discharge conduit being open 45 opposite said firing opening, and a door for said firing opening forming a hood for the open portion of said discharge conduit, said door comprising a plurality of segments arranged to slide one within the other, said segments being mounted 50 on pivots for swinging movement fore and aft with respect to said firing opening, the adjacent surfaces of said segments being coaxial with the axis of said pivots, each of said segments having means adapted to engage its next 55 succeeding segment for limiting the movement of said segments relatively to each other, and means for moving one of said segments for partially uncovering said firing opening, the continued movement of said segment causing successive 60 movement of each of the remaining segments by reason of their engaging relation to further uncover said opening.

6. In combination with a firebox having a backwall provided with a firing opening therethrough, a stoker discharge conduit attached to said backwall and delivering fuel to said opening, the upper portion of said discharge conduit being open opposite said firing opening, and a door for said firing opening forming a hood for the open portion of said discharge conduit, said door comprising a plurality of segments arranged to slide one within the other, said segments being mounted 70 on pivots for swinging movement fore and aft with respect to the firebox, the adjacent surfaces of said segments being coaxial with the

axis of said pivots, each of said segments having means adapted to engage its next succeeding segment for limiting the movement of said segments relatively to each other, and power means for swinging one of said segments along the next 5 succeeding segment for partially uncovering said opening, said power means including a motor comprising a reciprocable piston connected to said first named segment, a valve for controlling the movement of said piston and means for operating said valve, said first named segment being movable by said piston through an arc of approximately 90°, continued movement of said first named segment by said piston causing the remaining segments by reason of their engaging 10 relation to be successively moved to further uncover said firing opening.

7. In a firedoor apparatus, the combination of a door comprising a plurality of segments arranged to slide one within the other, the adjacent surfaces of said segments being parallel, and power means for moving one of said segments along the next succeeding segment for partially opening said door, said power means including a motor comprising a reciprocable piston 20 connected to said first named segment, a valve for controlling the movement of said piston and means for operating said valve, said segments being provided respectively with means whereby one segment will engage its succeeding 25 segment for limiting the movement of said segments relatively to each other, continued movement of said first named segment by said piston causing the remaining segments by reason of their engaging relation to be successively moved to open the door.

8. In a firedoor apparatus, the combination of a door comprising a plurality of segments arranged to slide one within the other, the adjacent surfaces of said segments being parallel, and power means for moving one of said segments 40 downwardly along the next succeeding segment for partially opening said door, said power means including a motor comprising a reciprocable piston connected to one of said segments, and a valve for controlling the movement of said piston, said piston moving said first named segment downwardly, said segments being provided respectively with means whereby one segment will engage its succeeding segment for limiting the 45 movement of said segments relatively to each other, continued downward movement of said first named segment by said piston causing the remaining segments by reason of their engaging relation to be successively moved downward to 50 open the door.

9. In a firedoor apparatus, the combination of a door comprising a plurality of segments arranged to slide one within the other, the adjacent surfaces of segments being parallel, a frame member for supporting said door, the segments of said door when in a closed position being slightly over-lapped and in engagement with each other to prevent relative downward movement therebetween, the segment which is adjacent said 60 frame having an adjacent edge in engagement with the rearward portion of said frame member to arrest downward movement of said segment, each segment overlapping the adjacent segment to the rear thereof, and power means for moving one of said segments upwardly along the next succeeding segment for partially opening said door, said power means including a motor comprising a reciprocable piston connected to one 65 of said segments, and a valve for controlling the 70 movement of said segments upwardly along the next succeeding segment for partially opening said door, said power means including a motor comprising a reciprocable piston connected to one of said segments, and a valve for controlling the 75

- movement of said piston, said piston moving said connected segment upwardly, said segment as it is moved upwardly under the next succeeding segment by said piston, engaging said succeeding segment whereby the continued upward movement of said connected segment by said piston will cause upward movement of said succeeding segment.
10. In combination with a firebox having a wall 10 provided with a firing opening therethrough, a stoker discharge conduit for delivering fuel to said opening, the discharge end of said conduit embracing said opening, the forward portion of said conduit being formed of a plurality of pivotally mounted segments arranged to slide within one another, and means arranged for successively sliding said segments within one another exposing substantially the entire firing opening.
11. In combination with a firebox having a wall 20 provided with a firing opening therethrough, a stoker discharge conduit for delivering fuel to said opening, the discharge end of said conduit embracing said opening, the forward portion of said conduit being formed of a plurality of pivotally mounted segments arranged to slide within one another, and means arranged for successively sliding said segments downwardly within one another exposing substantially the entire firing opening.
12. In combination with a firebox having a wall 30 provided with a firing opening therethrough, a stoker discharge conduit for delivering fuel to said opening, the discharge end of said conduit embracing said opening, the forward portion of said conduit being formed of a plurality of pivotally mounted segments arranged to slide within one another, and means arranged for successively sliding said segments upwardly within one another exposing substantially the entire firing opening.
13. In combination with a firebox having a wall 40 provided with a firing opening therethrough, a stoker discharge conduit for delivering fuel to said opening, the discharge end of said conduit embracing said opening, the forward portion of said conduit being formed of a plurality of segments mounted on pivots adjacent the lower mar-

ginal edge of said opening to swing fore and aft with respect to said firebox for covering and uncovering the firing opening, said segments being arranged to slide within one another.

14. In combination with a firebox having a wall 5 provided with a firing opening therethrough, a stoker discharge conduit for delivering fuel to said opening, the forward portion of said conduit being formed of a plurality of segments mounted on pivots adjacent the lower marginal edge of 10 said opening to swing fore and aft with respect to said firebox for covering and uncovering the firing opening, said segments being arranged to slide within one another, each of said segments having means adapted to engage its next succeeding segment limiting the movement of said segments relatively to each other, and means exterior of the conduit for moving one of said segments within the next succeeding segment for partially uncovering the firing opening, continued movement of said first named segment causing the remaining segments by reason of their engaging relation to be successively moved within one another to further uncover said firing opening.

15. In combination with a firebox having a wall 25 provided with a firing opening therethrough, a stoker discharge conduit for delivering fuel to said opening, the discharge end of said conduit embracing said opening, the forward portion of said conduit being formed of a plurality of pivotally mounted segments arranged to slide within one another, each of said segments having means for engaging its next succeeding segment limiting the movement of said segments relatively to each other, and power means including a motor comprising a reciprocable piston connected to one of said segments, a valve for controlling the movement of said piston and means for operating said valve, said segment being movable by said piston to partially uncover the firing opening, 30 continued movement of said piston causing the remaining segments by reason of their engaging relation to be successively moved to further uncover said firing opening.
